FLOAT VALVE

Edward M. May, Detroit, Mich.

Application November 1, 1937, Serial No. 172,116

4 Claims. (Cl. 137—104)

The invention relates to float valves suitable for controlling the flow of liquid refrigerant from the high pressure side to the low pressure side of mechanical refrigeration systems. In such refrigeration systems float control valves of two different types have been employed. In one type, the float is arranged on the outlet or low pressure side of the valve while in the other type the float is arranged on the inlet or high pressure side of the valve. The present invention relates to the second type of construction.

Refrigeration systems employing the high side float control valves have been subject to a serious difficulty in operation, namely, that air or other non-condensable gas in the system tends to accumulate in the float chamber of the valve and interfere with the proper operation of the valve. In such systems an effort is made, of course, to avoid the presence or entrance of air or other non-condensable gas but due to imperfect removal of air and gas at the outset or to leakage of air into the system during operation, the difficulty referred to is likely to be encountered and has constituted a serious drawback in the use of the high side float valve system.

The chief object of the present invention is the provision of an improved control valve with high side float which is adapted in operation to automatically purge air or other non-condensable gas from the high side of the system by discharging it past the valve into the low side of the system so that serious accumulation of such gas in the float chamber, with resultant interference with the operation of the system, is completely obviated.

Other objects, more or less incidental to the main object referred to, as well as the manner in which all of the objects are attained, will be apparent from the following description in connection with the accompanying drawing which illustrates two of the preferred embodiments of the invention.

In the drawing,

Fig. 1 is a longitudinal sectional view, with some parts in elevation, of one form of my improved valve in which the axis of the valve proper and its seat are vertically disposed, together with a diagrammatic showing of the elements of a mechanical refrigerating system in connection with which the valve is adapted for use.

Fig. 2 is a similar view of a modified form of valve construction in which the axis of the valve and its seat are horizontally disposed.

Referring first to the valve shown in Fig. 1, the device comprises a casing structure desig-

nated in its entirety by 1 and comprising a two-part float chamber structure 2 with a threaded inlet fitting 2a and a valve casing and outlet passage member 3 which is rigidly soldered or brazed to the casing section 2. 4 is a float with an arm 5 pivoted on a pin 6 carried by the upper end of the casing part 3. The casing part 3 has its bore fitted near its lower end with a valve seat 7 and is formed with ribs 8 which serve to guide a needle valve 9 that is pivotally connected by pin 10 with float arm 5. The outlet passage of the casing structure formed in the part 3 has its main inlet opening 11 at its upper end surrounding the stem of valve 9 and is provided intermediate its length with a supplementary inlet opening 12 of somewhat restricted capacity, as will later be explained. 13 is a pipe fitting attached to the outlet end of the casing member 3.

In the use of my improved float valve in a refrigeration system such as is indicated diagrammatically in Fig. 1, the inlet fitting 2a is connected with the liquid refrigerant line 14 of the system which in turn is connected with a condenser 15. The discharge fitting 13 of the valve is connected by conduit 16 to an evaporator 17 which in turn is connected by suction conduit 18 with the inlet side of a compressor 19 which delivers compressed refrigerant to the condenser 15.

The parts of the valve mechanism, and particularly the parts 3, 4, 5, 6, 7 and 9, are so constructed and operatively arranged that when the level of liquid in the float chamber rises to a level somewhat above the line X, the flotation force of the float is sufficient to overcome the pressure on the valve 9 and cause the latter to move to an open position. The valve 9 is subjected to the partially unbalanced pressure of the high side of the system and consequently, in the opening of the valve, the liquid in the float chamber rises above the level X which is adapted to sustain the valve in open position before the flotation force of the float is sufficient to overcome the unbalanced pressure on the valve. As soon as the valve leaves its seat and the unbalanced pressure on it is removed or largely reduced the float rises quickly to a position of less liquid immersion so that the valve is correspondingly quickly raised well off its seat to a substantially fully open position.

On the opening of the valve in the manner described, liquid refrigerant in the valve chamber B, under the action of gravity and the high side pressure in the system, is forced through

the valve seat into the low pressure side of the system. Meanwhile liquid refrigerant flows through passage 12 into chamber B but the caliber of the passage 12 is made sufficiently small in relation to the maximum rate at which liquid refrigerant is supplied through fitting 2a in the normal operation of the system under full load so that, after the opening of the valve 9, the liquid level in the float chamber continues to rise until the liquid overflows into the opening 11 whence it passes the open valve and is discharged to the low side of the system. The capacity of passage 12 is also smaller than that of the valve seat opening when the valve is fully open. Hence before the liquid overflows through passage 11 into chamber B and during the restricted flow through passage 12 gas in the space above the liquid in the float chamber A has access through chamber B to the valve seat opening so that any air or other non-condensable gas which may have accumulated in the float chamber A is at least in part discharged past the valve and into the low pressure side of the system. In determining the relative sizes of passages 12 and 7, account should of course be taken of the fact that the effective discharge pressure on the inlet end of the passage 12 is much smaller than that of passage 7.

When the supply of liquid refrigerant to the float chamber A is stopped or sufficiently reduced the level of the liquid in the chamber will begin to fall and the valve 9 will close upon its seat when the liquid falls to the level X. Then, if the valve is not tightly closed, liquid will continue to flow slowly past it until the liquid has fallen to some point between the levels represented by the lines X and Z where the combined unbalanced weight of the float and high side pressure on the valve exert sufficient pressure on the valve to seal it tightly. Thereupon the parts are in position for a repetition of the cycle which has been described.

It will be understood that the liquid level at which the immersion of the float is sufficient to open the valve will vary up or down with variation in the high side pressure of the system. It is to be observed, too, that with the refrigeration system operating under a relatively small heat load the rate of liquid refrigerant discharge into the float chamber A may not be sufficient to raise the liquid level in the chamber high enough to overflow through passage 11. Under these conditions all of the liquid discharged from the high side to the low side of the system will pass through the passage 12. Notwithstanding the slow rate of liquid discharge to the low side under such low load conditions, the opening of the valve occurs in much the same way under low load as under high load conditions. That is, with the valve closed on its seat, the liquid level in the float chamber A will continue to rise until it reaches some point above the line X before the flotation force is great enough to open the valve, whereupon the float rises quickly to a higher level to move the valve to a wide open position. Under such low load operating conditions the opportunity for discharge of accumulated gas from the float chamber to the low side of the system is even better than under the larger load conditions.

Generally speaking, the gas purging action of the valve increases with increase of the high side pressure of the system.

In the modified form of construction shown in Fig. 2 of the drawing a result equivalent to that

secured by the construction of Fig. 1 is attained in a somewhat different manner yet by the use of the same fundamental principle. In the modified construction the casing structure 20 comprises a casing section 20a affording a float chamber A' and a horizontally disposed valve casing and discharge member 20b which affords a chamber B' for the valve. 20c is an inlet fitting through which liquid is supplied to chamber A'. A float 21 has an arm 22 pivoted on a pin 23 carried by the member 20b. The casing part 20b is formed with a valve seat 24 and with ribs 25 which serve to guide a needle valve 26 pivotally connected by the pin 27 with the float arm 22.

The modified valve device is adapted to be connected into a closed circuit refrigeration system in the same manner as the valve first described.

In the operation of the second form of valve, the valve proper is held upon its seat by the pressure in the high side of the system until the liquid level in the float chamber A' rises to some level above that indicated in Fig. 2 by the line C. When the liquid reaches such level and the valve opens, by reason of the removal or reduction of the unbalanced pressure on the valve 26 the float 21 rises quickly so as to move the valve to a fully open position, as in the case of the first described form of construction. Liquid is then permitted to flow past the valve into the low pressure side of the system. As the liquid level falls in the float chamber A' the float falls with it and the valve is gradually moved toward its seat. However, the valve does not contact its seat until the surface of the liquid in chamber A' falls to the level indicated by the line C which is low enough to permit any gas above the liquid in the chamber A' to find access to the valve seat opening before the valve closes. Hence with the second form of construction there is provision for the discharge from the high pressure side to the low pressure side of the valve during each operative cycle of the valve of non-condensable gas that may accumulate in the upper part of the float chamber A'.

In the case of the first form of valve the discharge of gas past the valve is accomplished on the opening of the valve whereas in the second form of construction it is accomplished just prior to the closing of the valve, but it will be seen that in each case the casing structure, valve and float are constructed and operatively arranged to afford at some time while the valve is open access for gas above the liquid level in the float chamber to the valve seat opening so that any non-condensable gas that may accumulate in the float chamber is automatically discharged to the low pressure side of the system.

While in the constructions shown the valves proper are arranged to close with the flow rather than against the flow, it is to be understood that the invention in its broader aspects is not limited to this form of construction though I prefer such construction because it does not necessitate the use of a spring or equivalent means to close the valve and permits greater simplicity of construction and lower cost of production.

It will be understood, furthermore, that various other modifications of the construction may be employed without departing from the invention as defined in the appended claims.

What I claim is:

1. A unitary high side float valve for refriger-

ation systems comprising in combination a casing structure having an inlet passage for liquid refrigerant and an outlet passage for liquid refrigerant and forming a float chamber, a valve seat associated with the outlet passage, a valve arranged to cooperate with the seat to control passage of fluid therethrough, and means including a float in the said float chamber operatively associated with the valve and adapted to cause opening of the valve when the liquid level rises in the float chamber and closing of the valve when said level falls in the float chamber, the said outlet passage being constructed and arranged with an inlet thereto opening above the liquid level in the float chamber at which the 15 said means causes closing of the valve so as to afford at a time when the valve is open access for gas above the liquid level in the float chamber to the valve seat opening, whereby in the 20 operation of the valve gas in the float chamber is automatically discharged to the outlet side of the valve seat.

2. A float valve as defined in claim 1 in which the valve opens against the flow through the outlet passage.

3. A float valve as defined in claim 1 in which the outlet passage of the casing structure has, in addition to the inlet to said passage specified in claim 1, a second inlet opening into it at a level as low as the liquid level at which the valve closes upon its seat, the second inlet being restricted in comparison with the maximum rate at which the liquid is normally delivered into the float chamber in the operation of the device and of smaller effective capacity than the valve seat opening when the valve is in its fully open position.

4. A float valve as defined in claim 1 in which the valve seat opening and the outlet passage from its inlet end to the valve seat have at least a portion of their diameters disposed above the liquid level in the float chamber at which the valve closes.

EDWARD M. MAY.
